UNITED STATES PATENT OFFICE.

GEORGE H. F. HOLY, OF PITTSBURGH, PENNSYLVANIA, ASSIGNOR TO WESTINGHOUSE ELECTRIC AND MANUFACTURING COMPANY, A CORPORATION OF PENNSYLVANIA.

VEHICLE SUSPENSION.

1,411,027.

Specification of Letters Patent. Patented Mar. 28, 1922.

Application filed September 17, 1920. Serial No. 410,876.

To all whom it may concern:

Be it known that I, GEORGE H. F. HOLY, a citizen of the United States, and a resident of Pittsburgh, in the county of Allegheny and State of Pennsylvania, have invented a new and useful Improvement in Vehicle Suspensions, of which the following is a specification.

My invention relates to vehicle suspensions, and particularly to suspension mechanism for vehicles having more than two wheels, wherein it is desired to maintain a uniform distribution of weight upon the various wheels through the use of equalizing mechanism.

In the operation of railroad locomotives it is desirable—and in some cases necessary—to maintain a constant load on each of the wheels and to equalize the load thereon.

For instance, when a wheel enters a depression in the rail, the tendency is for its load to be assumed by the other wheels, and, being lightened of its load, it is in danger of becoming derailed. On the other hand, when

a wheel encounters an elevation on the rail, the tendency is for it to assume an added portion of the load, with the result that an undue strain is thrown upon both it and the rail, and there is a possibility of derailment.

To overcome these difficulties, which become very pronounced in high-speed operation, various schemes have been proposed, such as three-point equalized supporting mechanism wherein each of the side frames

of a locomotive, at one end, is hung upon equalizing levers which are in turn supported from the springs adjacent to the rear end of the locomotive, while at their other ends, the frames are supported from a cross-equalizing

lever connected to the spring adjacent the front end of the locomotive. This arrangement produces the effect of a three-point suspension—two on opposite sides at the rear of the locomotive, and one near the front of the locomotive, between the side frames.

The objection to cross equalization lies in the fact that additional parts are required, especially in locomotives having their side frames located outside of the wheels, and

the parts occupy space which may be used advantageously for other purposes.

By my construction I provide a distribution of the spring-borne weights in such manner that a two-point supporting effect is secured on one side of the locomotive and a one-point supporting effect is secured on the other side thereof. This construction permits the operation of a locomotive freely in either direction, and leaves the space formerly occupied by the cross equalizing parts clear for the placing and removal of the motors or other mechanism.

Referring now to the drawings,

Figure 1 is a plan view of the supporting structure of a six-wheeled locomotive with my invention applied thereto.

Fig. 2 is a view in side elevation looking in the direction of the arrows II—II of Fig. 1.

Fig. 3 is a view in side elevation looking in the direction of the arrows III—III of Fig. 2, and

Figs. 4 and 5 are diagrammatic illustrations of the manner in which my invention may be applied to an eight-wheel and a four-wheel locomotive, respectively.

On the driving axles 6 are carried the usual journal bearings 7 for supporting the side frames 8 and 9 of the locomotive and the parts carried thereon.

Referring more particularly to Fig. 2, it will be seen that semi-elliptical springs 10, 11 and 12 rest upon saddles 13 supported by the journal bearings 7. The spring 12, at its outer end, is connected to the frame 8 by a link 15. The inner end of spring 12 is connected to the frame 8 by a link 16. The equalized support furnished by the spring 12 and link members 15 and 16 constitutes one point of suspension.

Spring 11, at its one end, is connected to the side frame 8 by a link 17, and at its other end is connected to an equalizing lever 18 by a link 19. The outer end of the spring 10 is connected to the side frame by a link 14, and its inner end is connected to the lever 18 by a link member 20. The side frame 8 is supported on the equalizing lever 18 by

means of a hinge pin 21. The equalized support furnished to the frame by the springs 10 and 11, through the links 17 and 14 and the equalizing lever 18, constitutes a 5 second point of suspension.

Referring now more especially to Fig. 3, the side frame 9 is connected to one end of a spring 22 by a link 23 and to one end of a spring 24 by a link 25. The inner ends 10 of the springs 22 and 24 are connected by links 26 and 27, respectively, to equalizing levers 28 and 29, respectively, and a spring 30 is connected by links 31 and 32 to the equalizing levers 28 and 29. The frame is 15 supported on the equalizing levers 28 and 29 by hinge pins 33 and 34, respectively. The suspension of the side frame 9 from links 23 and 25 and from the equalizing levers 28 and 29 constitutes the third point 20 of support.

It will be seen from Fig. 3 that the link and pivoted bar connections between the side frame and the springs are such that any deviation from the horizontal by either of 25 the wheels brings the spring connections into play to effect a proper disposition of the weight, and to compensate for the irregularities in the track which may have caused such deviation.

With regard to the construction shown 30 in Fig. 2, it will be seen that if the wheel 35 encounters a depression or elevation, the weight of the locomotive will rock on the point of support furnished by the connections between the frame 8 and the springs 35 10 and 11, and the supporting point furnished by the connections between the springs 22, 30 and 24, thus maintaining a constant load on the wheel 35. On the other 40 hand, if wheel 36 is caused to deviate from the horizontal an equalization is effected between it and wheel 37, and the mass of the locomotive rocks on the point of support furnished by the spring 12 and the point 45 of support furnished by the springs 22, 30 and 24 and their equalizing connections.

Should either of the wheels of Fig. 3 encounter an elevation or depression, the equalizing connections of the springs 22, 30 50 and 24 are brought into play to compensate for irregularities in the track and to maintain approximately a constant weight on each of the wheels and the mass of the locomotive pivots upon the two points of support furnished by the spring connections of Fig. 2.

In Fig. 4 I have illustrated the manner in which the frame may be connected to the springs of an eight-wheeled locomotive, to 60 secure a three-point support. By connecting the links and equalizing bars at the points marked "A" to the one side frame I procure one point of support. On the other side of the locomotive two adjacent springs 65 are connected to the locomotive frame,

through the proper links and equalizing lever, at the points marked "B", thus securing another point of support. The other two springs are connected to the locomotive frame at the points marked "C" to provide 70 the third point of suspension. The action in an eight-wheel construction is the same as that described for a six-wheel structure, that is, the equalizing connections are such that the points "A" operate as a single 75 point of support; the equalizing connections between points "B" constitute another point of support, and in like manner the combined effect at the points "C" is that of a third 80 point of support.

In Fig. 5, one point of support is secured by means of the connections "D"; another point by connections "E", and a third point by the connections "F".

It will be apparent that various modifications might be made in the device without departing from the scope of the invention as defined in the claims. The invention is shown as applied to locomotives having their side frames located between the wheels, but 90 it can as well be applied to those with frames outside of the wheels.

I claim as my invention:—

1. In a vehicle suspension, means for effecting a three-point spring equalization 95 disposed only in a direction longitudinally of the vehicle.

2. In a vehicle suspension, means for effecting one point of spring equalization along one longitudinal side of the vehicle, 100 and means for effecting two points of spring equalization along the other longitudinal side of the vehicle.

3. In a vehicle suspension, a plurality of 105 equalizing springs for supporting the superstructure of a vehicle, means for centralizing the operation of one set of equalizing springs at a point approximately midway of one longitudinal side of the vehicle, means for effecting centralization of the 110 operation of a set of equalizing springs on the opposite side of the vehicle at a point in advance of the first named point, and means for centralizing the operation of another set of equalizing springs on said opposite side, 115 at a point behind the first named point.

4. In a vehicle suspension, a single series of equalizing connections for effecting a uniform distribution of weight on the wheels at one side of the vehicle, and two series of 120 equalizing connections for effecting a uniform distribution of weight on the wheels at the other side of the vehicle.

5. In a vehicle suspension, a supporting frame, a plurality of longitudinally disposed 125 leaf springs arranged in tandem along each side of the vehicle, supporting link members connecting the frame to the outer extremities of the four end springs, link members forming an equalizing connection between the 130

free ends of the springs on one side of the vehicle, means whereby the frame is supported from said equalizing connecting members, two independent sets of equalizing members suspended from the free ends of the springs on the other side of the vehicle, and means whereby the frame is supported

from each of the said two sets of equalizing members.

In testimony whereof, I have hereunto 10
subscribed my name this 30th day of Au-
gust, 1920.

GEORGE H. F. HOLY.
